COMBINATION CRADLE AND POWER-DRIVEN STRAIGHTENER FOR COILED SHEET METAL

Albert F. Lehmann, Detroit, Mich., assignor to Sesco Incorporated, Detroit, Mich., a corporation of Michigan

Application January 20, 1958, Serial No. 49,299

Term of patent 3½ years

(Cl. D54—14)

Fig. 1

FIG. 2

Fig. 1 is a perspective view showing the front and one end of a combination cradle and power-driven straightener for coiled sheet metal embodying my new design.

Fig. 2 is a perspective view showing the back and the other end of the combination cradle and power-driven straightener for coiled sheet metal shown in Fig. 1.

The dominant features are those portions shown by solid lines in the drawings.

I claim:

The ornamental design for a combination cradle and power-driven straightener for coiled sheet metal, substantially as shown and described.
